FIG. 1

FIG. 2

Inventor

Eleanor P. Vance,

By *James L. Morris* Attorney

Patented Oct. 14, 1924.

1,511,921

UNITED STATES PATENT OFFICE.

ELEANOR P. VANCE, OF TRYON, NORTH CAROLINA.

TOY.

Application filed April 5, 1922. Serial No. 549,670.

To all whom it may concern:

Be it known that I, ELEANOR P. VANCE, a citizen of the United States, residing at Tryon, in the county of Polk and State of North Carolina, have invented new and useful Improvements in Toys, of which the following is a specification.

This invention relates to toys and proposes the construction of such a device wherein a mounted oscillatable striker, which is preferably formed in the simulation of an animal, is adapted, when actuated to co-act with a projectile, to propel the latter in the general direction of a suitable goal or target.

One of the objects of the invention is to arrange the resiliently supported striker in normally spaced relation to the projectile in order that a hammer blow will be delivered to the latter when the striker is actuated.

Another object of the invention is to give the projectile an oval or non-spherical conformation so as to impart to said projectile an element of chance of variation in its path of travel upon successive blows of the striker.

Another object of the invention is to so construct the support for said projectile, as to provide a face with which the striker, when actuated, will cooperate and which will form a narrowing angle between the sides of which the projectile is pressed and thereby expelled in the direction toward said goal or target.

Still another object of the invention is the provision of a support in the form of a pedestal having a concave face functioning to retain said projectile in position to be engaged by the striker, the sloping sides of said face serving to elevate the trajectory of said projectile, when struck.

A further object of the invention is the provision of a hole or equivalent goal or target, toward which the projectile is driven by the striker, said hole being so placed and proportioned as to increase to an interesting degree the chance of said projectile entering said hole, the factors of uncertainty inherent in the action of the striker, the shape of the projectile, and the contour of the face of the support making it improbable to predetermine the result of a particular stroke, thus enhancing the game-like character of the device.

With the above and other objects in view, my invention consists in the improved toy illustrated in the accompanying drawings, described in the following specification, and particularly claimed, and in such variations and modifications thereof as will be obvious to those skilled in the art to which my invention relates.

In the drawings accompanying and forming a part of this specification, and where in the preferred embodiment of my invention is illustrated:

Figure 1 is a perspective view showing one embodiment of the invention, the striker, which has the form of a rabbit being shown in neutral or inoperative position.

Figure 2 is a side elevation showing the striker in tensioned position and the projectile on the support, the dotted outline of the parts showing, respectively, the position of the striker when engaging the projectile, and the latter projected through the hole or target.

Referring now in detail to the figures the numeral 1 represents a base to one end of which the upright 2 is secured in any suitable manner, said upright being provided with a suitable goal, which is here represented by the hole 3. The striker 4 which includes the leaf spring 5 or its equivalent, is resiliently attached to the base 1. The striker preferably comprises a striking element of wood or composition-board which in the present instance has the form of a rabbit having the fore-legs 6 attached to the spring 5 and the rear legs 7 in elevated position for engaging the projectile 8. The leaf spring 5 is secured to the fore-legs in such a way as to cause said rabbit, when the spring 5 is in position of repose to be sustained uprightly with the rear legs 7 in spaced relation to the projectile 8. The striker is actuated by being pulled forwardly into the position shown in full lines in Figure 2 and then released, springing back to the dotted line position of Figure 2, in which position the legs 7 deliver a hammer blow to the projectile 8 driving it toward the hole or target 3. The projectile is of a non-spherical shape, and is here shown as an oval, to represent an egg. The shape of the projectile is such that a very slight displacement of the same relative to the striker, 110

will result in slightly different paths of travel of said projectile on different strokes, imparting to the toy an element of chance as to the probability of the projectile entering the hole 3 when driven theretoward by the striker.

The projectile 8 is seated upon the top of a pedestal 9, which comprises a stem having a head 10 constructed with a concave supporting face 11. The slightly sloping sides of said supporting face assist in retaining the projectile upon the pedestal and also function to guide the projectile upward as it is driven from the support by the striker, 10 elevating its trajectory and increasing the chance of it going through the hole 3 in the upright 2. It will be noted from Figure 2 that the striker oscillates in a circular arc so that when the rear legs 7 of the rabbit approach the support 9 their motion is downward the legs assuming a narrowing angularity toward the supporting face 10 as the striker approaches the point of engagement with the projectile. This causes the projectile to be engaged by the sides of this narrowing angle, said projectile being squeezed out from between the said inclined surfaces and being expelled in the direction of the hole 3.

It will thus be understood that the motion imparted to the projectile is varied not only by the shape of the latter but by the composite forces acting upon it through the striker, namely the hammer blow delivered to it upon initial engagement with the striker and the explosive force impressed upon it by the sides of the acute angle formed between the striker and the supporting face of the pedestal, as said elements come together, and that the dished shape of the supporting face also has a modifying effect upon the direction of travel of said projectile. The hole 3 or an equivalent goal is located at an appropriate elevation, and is of the appropriate size to assure that the projectile will pass therethrough a sufficient number of times for a given number of operations of the striker to make the toy interesting as a game, but not so frequently as to render the actuation of the striker an assurance of a successful shot. The projectile may be a freely moving body, but is here shown as held captive by the cord 12 which safeguards against the loss of the projectile.

It is of course obvious that any other representation for the figure of the strike than the one here shown may be adopted without violating the spirit of the invention, and that the projectile may be made of any shape which conforms to its non-spherical characteristic. The specific details of construction and configuration of parts described herein may be modified in various ways without sacrificing the advantages of

the invention or departing from the scope thereof as defined in the appended claims.

Having described my invention what I claim and desire to secure by Letters Patent, is:—

1. A toy comprising a base, a member provided with a goal supported by said base, an oscillatory striker secured to said base having a portion for engagement with a projectile, a pedestal mounted on said base between said goal and said striker, said pedestal having a concave upwardly directed face, said striker being of greater height than the pedestal and secured to the base at such distance from the pedestal as to cause the path traversed by the projectile engaging portion, when oscillated to intersect the supporting face of said pedestal, a projectile adapted to be freely seated upon said supporting face, the latter and the engaging portion of the striker being divergent toward the goal at the moment of contact between the striker and projectile, said projectile being guided by the sloping walls of said supporting face whereby the trajectory of said projectile in its path of travel toward said goal is elevated.

2. A toy comprising a base, a member provided with a goal supported by said base, an oscillatory striker secured to said base having a portion for engagement with a projectile, a pedestal mounted on said base between said goal and said striker, said pedestal having a concave upwardly directed face, said striker being of greater height than the pedestal and secured to the base at such distance from the pedestal as to cause the path traversed by the projectile engaging portion, when oscillated, to intersect the supporting face of said pedestal, a captive projectile adapted to be freely seated upon said supporting face, the latter and the engaging portion of the striker being divergent toward the goal at the moment of contact between the striker and projectile, said projectile being guided by the sloping walls of said supporting face whereby the trajectory of said projectile in its path of travel toward said goal is elevated.

3. A toy comprising a base, a member provided with a goal supported by said base, an oscillatory striker secured to said base having a portion for engagement with a projectile, a pedestal mounted on said base between said goal and said striker, said pedestal having a concave upwardly directed face, said striker being of greater height than the pedestal and secured to the base at such distance from the pedestal as to cause the path traversed by the projectile engaging portion, when oscillated, to intersect the supporting face of said pedestal, a non-spherical captive projectile adapted to be freely seated upon said supporting face, the

latter and the engaging portion of the striker being divergent toward the goal at the moment of contact between the striker and projectile, said projectile being guided by the sloping walls of said supporting face whereby the trajectory of said projectile in its path of travel toward said goal is elevated.

In testimony whereof I have hereunto set my hand in presence of two subscribing ¹⁰ witnesses.

ELEANOR P. VANCE.
